United States Patent Office

Des. 216,010
Patented Nov. 18, 1969

216,010

TRAILER

Robert S. Hudson, Fridley, Minn., assignor to K-Boose,
Inc., St. Paul, Minn., a corporation of Minnesota

Filed July 24, 1968, Ser. No. 12,872

Term of patent 14 years

Int. Cl. D12—10

U.S. Cl. D14—3

FIG. 1 is a left side elevational view of the trailer of this invention;

FIG. 2 is a right side elevational view thereof;

FIG. 3 is a top plan view thereof;

FIG. 4 is a front elevational view thereof;

FIG. 5 is a rear elevational view thereof;

FIG. 6 is a left side elevational view of the trailer of this invention with the tent porch not extended;

FIG. 7 is a right side elevational view thereof;

FIG. 8 is a top plan view thereof;

FIG. 9 is a front elevational view thereof; and

FIG. 10 is a rear elevational view thereof.

I claim:

The ornamental design for a trailer, as shown and described.
